WATER CONTROL FOR SPIGOTS, ETC.

Filed April 28, 1944

Inventor,
LANDON W. FERRELL.

By C. B. Vrooman & Co.
The Chromey.

UNITED STATES PATENT OFFICE

2,412,037

WATER CONTROL FOR SPIGOTS, ETC.

Landon W. Ferrell, Knoxville, Tenn.

Application April 28, 1944, Serial No. 533,192

3 Claims. (CL 236—12)

1

This invention relates to a thermostatic water control for bath tubs, kitchen sinks, wash basins, showers, etc.

An object of the invention is the provision of simple and efficient means for blending together hot and cold water when desired, or when the operator desires he can easily adjust the mechanism for discharging only cold water.

Another object of the invention is the construction of a mechanism of the character described, which can be set into a wall of a room where it will be hidden from view and only the indicator disc or plate with the pointer exposed to view, thereby causing the mechanism to be attractive in appearance.

A further object of the invention is the construction of a novel and efficient valve whereby the flow of hot water or cold water, or the blending of the two, can be admirably controlled.

With the foregoing and other objects in view, my invention comprises certain novel constructions, combinations, and arrangements of parts as will be hereinafter fully described, illustrated in the accompanying drawing, and more particularly pointed out in the appended claims.

In the drawing:

Figure 1 is a view partly in elevation and partly in longitudinal section of a mechanism constructed in accordance with the present invention, and showing said mechanism applied within a wall of a building.

Figure 2 is a vertical sectional view of the mechanism taken at right angles to the disclosure in Figure 1.

Figure 3 is a sectional view taken on line 3—3, Fig. 2, and looking in the direction of the arrows.

Figure 4 is a sectional view taken on line 4—4, Figure 2, and looking in the direction of the arrows.

Figure 5 is a fragmentary perspective view of 40 the valve sleeves with the rotary valve therein.

Figure 6 is an enlarged transverse sectional view of one of the valve sleeves and a portion of the rotary valve, while

Figure 7 is a similar view of the other valve sleeve and the rotary valve therein.

Figure 8 is an enlarged elevated view of the indicator disc and the pointer.

Figure 9 is an enlarged fragmentary view of a valve sleeve and the valve casing, showing the set screw for holding these parts securely together.

Referring to the drawing in which I have shown the preferred embodiment of my invention, I designate a valve casing of a cylindrical type, in

2

the two ends of which are screwed valve sleeves 2 and 3, Fig. 4. Each valve sleeve comprises a hub portion 4 on the inner end of which is the reduced cylindrical extension 5. Threaded into valve sleeve 2 is the hot water pipe 6, and threaded into the valve sleeve 3 is the cold water pipe 7. A cylindrical rotary valve 8 is mounted within the valve sleeves 2 and 3. This rotary valve has a central partition 9, and on its outside it is provided with an outwardly extending finger 10; finger 10 moves or swings between the contiguous inner ends of the valve sleeves 2 and 3. By means of plug 11, Fig. 2, access is obtained to the interior of valve casing 1, whereby the operator may connect the link 12 to the finger 10, or he may clean out the valve casing 1, as he desires. Detachably secured to the top of valve casing 1 is a housing 13; this housing has guide grooves 14 formed on its inner face; these grooves 14 are arranged in vertical position and are in alignment, whereby the ribs 15 are received, and thereby permitting the thermostat frame 16 to have a vertical sliding movement within housing 13. Within frame 16 is a common type thermostat 17; thermostat 17 has a depending stem 18, which stem is pivotally connected to the upper end of link 12, whereas the lower end of link 12 is pivotally connected to said finger 10. Integral with and extending upwardly from housing 13 is a globe portion 19. The upper portion of the globe portion 19 is threaded at 20, to receive any suitable piping as indicated by dotted lines 21, Fig. 1, which piping is connected to a spigot or faucet 22.

A shaft 23 (Fig. 2) extends through tube 24, sleeve 25, and its inner end is positioned in the globe portion 19. A link 26 is in the globe portion 19 and said link is connected at its lower end in a pivotal manner to the pair of lugs 27 that extends upward from the top of frame 16. A suitable connection 28 pivotally fastens the upper end of link 26 to rotary shaft 23. The sleeve 25 is threaded at its inner end into portion 29 of the globe 19, and the tube 24 is threaded on the outer closed end of sleeve 25. A set screw 30 serves to securely retain tube 24 on sleeve 25. On the outer end of tube 24 is an integral indicating disc 31; disc 31 is preferably placed against a wall 32, with the rest of the apparatus either built in the wall or behind the same, whereby only the disc 31 and pointer 33 show in the room, whereby an excellent appearance is produced. The pointer 33 is securely fastened to the outer end of shaft 23. On the outer face of disc

31 are designations "Hot," "Medium," and "Cold" for the purpose hereinafter described.

The valve sleeves 2 and 3 are securely fastened together by set screws 34 (Fig. 9).

The valve sleeve 2 is provided with a plurality of parallel transversely positioned elongated slots 35, through which hot water is adapted to pass. The right hand portion of rotary valve 8 is provided with ports or openings 36, which are adapted to register with said elongated openings 35. The valve sleeve 3 is provided with aligned ports or openings 37 through which cold water is adapted to pass. The left hand portion of rotary valve 8 is provided with a plurality of aligned ports or openings 38 that are adapted to register with openings 37, for allowing cold water to pass from pipe 1 into the valve casing 1 and in due course be discharged through the spigot 22.

When the mechanism is in the position shown in Figures 1 and 2, the only escape for the water when the spigot or faucet 22 is turned on is through openings 35 and 36. Then as the water passes up and around the thermostat 17, said thermostat will expand and lower the opening 36 to the bottom of the elongated or oblong openings 35, which is the limit of expansion for the thermostat, and since openings 37 and 38 remain closed, hot water is all that comes from the faucet 22.

Then when the pointer 33 is set in the position of "medium," the thermostat 17 is lowered within the housing 18, placing the openings 37 and 38 tangent with each other and the openings 36 are lowered to the bottom of openings 35. This again allows the hot water to enter first and as it passes over the thermostat, openings 37 and 38 start opening, and openings 36 and 35 begin closing, which gives a medium or any temperature water desired between hot and cold.

When the pointer 33 is set to indicate "cold," openings or ports 37 and 38 are entirely open, and openings 35 and 36 are entirely closed. Therefore, since cold water has no effect upon a thermostat, the sleeve valve 8 remains in this position and cold water is all that comes from the faucet 22.

While I have described the preferred embodiment of my invention and illustrated the same in the accompanying drawing, certain minor changes or alterations may appear to one skilled in the art to which this invention relates during the extensive manufacture of the same, and I, therefore, reserve the right to make such alterations or changes as shall fairly fall within the scope of the appended claims.

What I claim is:

1. In a mechanism of the class described, the combination of a valve casing, separate sleeves in said valve casing and extending inwardly from its ends, one of said sleeves being provided with a plurality of hot water openings at its top and the other sleeve being provided with a plurality of cold water openings on its side, a rotary valve within said sleeves provided with sets of hot and cold water openings being adapted to register with the corresponding openings of said sleeves at predetermined times, a thermostat housing on said valve casing, a thermostat frame slidably mounted within said housing, a thermostat within said frame, means connecting said thermostat to said rotary valve only between the inner ends of said sleeves, indicating means including a disc with different temperature markings thereon and a pointer cooperating with said

disc, and means connecting said pointer to said slideable thermostat frame, whereby when said pointer is manually adjusted with reference to the temperature markings on said disc said rotary valve will be rotated to bring like openings on said valve and sleeves in registering position to control the temperature of water flowing through the valve casing.

2. In a mechanism of the class described, the combination of a valve casing, separate sleeves in said valve casing and extending inwardly from its ends, one of said sleeves being provided with a plurality of aligned elongated hot water openings at its top and the other sleeve being provided with a plurality of aligned cold water openings in its side, a rotary valve within said sleeves and provided with a set of hot and a set of cold water openings arranged in alignment thereon, a thermostat housing on said valve casing, said housing provided in its inner wall with vertical slots, a thermostat frame provided with vertical ribs, said ribs positioned in said vertical slots, a thermostat within said frame, a finger extending from said rotary valve only between the inner ends of said sleeves, means pivotally connecting said finger to said thermostat, an indicating disc provided with "hot," "medium" and "cold" indications, a pointer adapted to be turned by manual exertion to either one of said indications, means connecting said pointer to said thermostat frame, whereby when the pointer is manually operated to move it in a registering position with said indications on said disc said thermostat frame will be moved to different positions within said housing, whereby when the frame is in its uppermost position within the housing the hot water set of the openings on the rotary valve will be registering with the upper portions of the elongated hot water openings on one sleeve, while at the same time the cold water openings of the valve will be closed; while manual operation of the pointer to lower said thermostat frame to its lowest position within the housing will cause the cold water set of openings on the rotary valve to register with the cold water opening on the side of one sleeve.

3. In a mechanism of the class described, the combination of a valve casing, separate sleeves within said valve casing and spaced apart at their inner ends, a single rotary valve spanning the space between the inner ends of said sleeves and having its ends extending into said sleeves, said valve provided near one end with a set of hot water openings and near its other end with a set of cold water openings, one of said sleeves provided at its top with hot water openings and the other sleeve provided on its side with cold water openings, a thermostat casing on said valve casing, a slideable thermostat frame entirely within said thermostat casing, a thermostat within said thermostat frame, a finger between the inner ends of said sleeves and on said rotary valve, means connecting said finger to said thermostat, a temperature indicating means connected to said thermostat frame, and said temperature indicating means including manually operated means, whereby said thermostat frame and the thermostat can be positioned in said thermostat casing causing the hot water openings of valve and sleeve to register or upon another positioning of said thermostat frame the cold water openings on valve and sleeve will register, substantially as shown and described.

LANDON W. FERRELL.
